UNITED STATES PATENT OFFICE.

ALBERT VALENTINE, OF THURMAN, IOWA.

FLYING-MACHINE.

1,015,656.

Specification of Letters Patent. Patented Jan. 23, 1912.

Application filed April 13, 1911. Serial No. 620,773.

To all whom it may concern:

Be it known that I, ALBERT VALENTINE, a citizen of the United States, residing at Thurman, in the county of Fremont and 5 State of Iowa, have invented new and useful Improvements in Flying-Machines, of which the following is a specification.

This invention relates to flying machines of the heavier-than-air class, and particularly to those of the helicopter type.

The object of the invention is to provide a machine of this character having a novel construction and arrangement of lifting and driving propellers, and means for controlling the same, whereby the machine may be started straight up from the ground, propelled and steered in any desired direction, caused to "hover" at any elevation, and readily guided and controlled in its descent.

20 The invention consists of the features of construction, combination and arrangement of parts, hereinafter fully described and claimed, reference being had to the accompanying drawings, in which:

25 Figure 1 is a front elevation of a flying machine embodying my invention, showing the propellers arranged in a horizontal position. Fig. 2 is a side elevation of the same, showing in dotted lines the propellers tilted 30 for forward propulsion. Fig. 3 is a vertical longitudinal section through the same. Fig. 4 is an enlarged vertical transverse section through the propellers and the gearing therefor. Figs. 5 and 6 are perspective views 35 of the propellers.

In carrying my invention into practice, I provide a car or cage 1 of any suitable form and construction, which is suspended from a frame comprising uprights 2 suitably connected and braced. The car or cage 1 is 40 designed to support the driving motor 3 and the pilot and passengers, if any, together with the controlling devices.

45 Arranged between the upper ends of the uprights 2 is a propeller supporting frame consisting of end pieces 4 and top and bottom pieces 5 and 6, which may be rigidly united and braced in any approved manner. This frame is provided at its opposite ends 50 with short shanks or trunnions 8 and 9 journaled in suitable bearings 10 at the upper ends of said standards whereby said supporting frame, which normally stands in a vertical position, may be tilted in a fore and 55 aft direction.

For the purpose of tilting the supporting

frame suitable mechanism is employed, comprising a drum or pulley 11 upon one of the short shafts or trunnions, which is engaged by ropes or cables 12 extending downwardly 60 into the car and connected with a suitable operating or controlling device 13, whereby motion may be communicated to the drum to swing the frame on the trunnions. The operating device is provided with a spring-actuated pawl or dog 13 adapted to engage a rack 14 on the car, whereby the supporting frame may be locked securely in adjusted position.

65 Journalled in suitable bearings on the supporting frame is a pair of concentrically arranged shafts 15 and 16, the shaft 16 being hollow and arranged to inclose the shaft 15. The shaft 15 is journaled at its lower end in a bearing in the bottom piece 6 of the supporting frame and extends upwardly through the shaft 16 and carries at its upper end a propeller 17, while the shaft 16 is journaled upon the shaft 15 and in a 70 suitable bearing in the top piece 5 of the supporting frame and carries a lower propeller 18.

75 The propellers are adapted to be rotated at the same rate of speed in opposite directions and are driven by gearing comprising 80 beveled gears 19 and 20 on the respective shafts meshing with a gear 21 carried by a shaft 22 arranged at one end of the supporting frame and journaled in the adjacent end piece 4 of said frame and a parallel supporting piece 23, which gear 21 serves as a transmission gear for simultaneously rotating the gears 19 and 20 in opposite directions. A sprocket wheel 24 is mounted on the shaft 22 and is connected with the drive 85 shaft of the motor by a chain 25, whereby the gearing is driven. The propellers 17 and 18 are generally similar in construction, each comprising a suitable hub 26 from which radiate upper and lower pairs of 90 arms 27 and 28 connected at their outer ends with rims 29 and reinforced at their inner ends by suitable braces 30. Fixed to the hub and rims and extending between the sets of arms are propeller blades 31 inclined at an angle to the plane of rotation 95 of the propeller to present the necessary angle of incidence for propelling and supporting action, the blades of one propeller inclining in one direction, while the blades 100 of the other propeller incline in the reverse direction.

As stated, the propellers are driven in opposite directions at corresponding rates of speed, and thus each counteracts the other against any tendency to swerve the machine laterally from its course. The blades of both propellers operate to force the air in a downward and rearward direction, by which both a sustaining and a working thrust is obtained. When the propellers are arranged in a horizontal position and driven at a determined rate of speed, they will operate to lift the machine directly in the air, so that a straight start may be made from the surface of the ground. When the machine has reached a desired elevation, the propellers may be tilted in a downward and forward direction to lie at an angle to the path of travel, as indicated in dotted lines in Fig. 2, by which they will operate to both sustain the machine and propel the same in a forward direction. By decreasing the speed of the propellers below sustainment limit, the machine may be caused to descend slowly to the ground, and by properly proportioning the speed while the propellers are arranged in a horizontal position the machine may be caused to "hover" as will be readily understood.

As the elevation of the machine may be controlled by means of the propellers, the necessity of employing a horizontal rudder is obviated. For the purpose, however, of steering the machine laterally, a vertical rudder 32 is provided and extends laterally from the upright frame portion or tower 2. The rudder is connected at its forward end to a staff 33 pivotally mounted upon a support 34 between the uprights to swing later-

ally, said staff being connected with controlling cords or cables 35 leading to an operating device 36 on the cage or car, by which the rudder may be controlled. It will, of course, be understood that suitable clutch mechanism may be employed for throwing the gearing into and out of action and that the speed of rotation of the propellers may be controlled either by the use of variable speed gearing or by directly regulating the speed of the motor.

Having thus described the invention, I claim:

A flying machine comprising a car, uprights projecting therefrom, an open rectangular frame provided with trunnions journaled in bearings on said uprights to swing in a fore and aft direction, concentric vertical shafts journaled on said frame and carrying superposed bevel gears, a transmission shaft mounted on the frame and carrying a bevel gear meshing with the first-named gears for driving said vertical shafts in opposite directions, superposed propellers mounted upon the vertical shafts above said frame and having blades inclined in opposite directions, a drum fixed to one of said trunnions, means for turning said drum to tilt the frame in one direction or the other, a motor on the car, and gearing between the motor and said transverse shaft.

In testimony whereof I affix my signature in presence of two witnesses.

ALBERT VALENTINE.
